PROTECTED BLADE

Joseph M. Bowen, West Quincy, Mass., assignor
to Gillette Safety Razor Company, Boston,
Mass., a corporation of Delaware

Application April 27, 1937, Serial No. 139,264

5 Claims. (Cl. 206—46)

This invention relates to the packaging of fine edged blades, such for example as safety razor blades. In one aspect it consists in an end notched or recessed blade protected by a wrapper 5 of sheet material and positively held therein against displacement by being interlocked with the wrapper. A protected blade of this general type is disclosed and claimed in my prior application, Ser. No. 101,281, filed September 17, 1936.

10 In another aspect the present invention consists in the adaptation of the broad principle of my earlier invention to the wrapping of blades having a recess provided at any point between their end corners.

15 In handling safety razor blades under commercial conditions of transportation and distribution and in the more or less casual treatment of such blades by the user, the extremely fine, keen edge of the blade is likely to become dulled by being brought into contact with its wrapping either at a fold vertex or by being drawn across or cutting the wrapper in being removed therefrom. On this account the best and most skillful efforts of the manufacturer in sharpening blades are often brought to naught because of the damage done 20 to the fragile and delicate structure of the blade edge after it has been brought to the keenest possible shaving condition and before the shaving operation is actually undertaken.

25 With these conditions in view an important object of the present invention is to provide a novel wrapper in which an end notched blade may be fully enclosed and held positively in such position that its cutting edge is protected at all times 30 from direct contact with the fold vertex lines of the wrapper. I have discovered that the desired results may be accomplished by shaping the end tabs of the wrapper to present a neck or portion of reduced width which may be passed through 35 or into the end cavities of the blade and so interlocked with the blade that transverse shifting thereof in the wrapper is positively prevented. Then, by folding side flaps of the wrapper on lines outside the sharp edge or edges of the blade, 40 the latter is held positively out of contact with the adjacent fold vertex lines of the wrapper.

45 Preferably and as herein shown the reduced portions or necks in the end tabs carry enlarged ends or terminal portions which are substantially 50 wider than the recesses of the blade. The end tabs are thus shaped for interlocking with the blade in a longitudinal sense and so prevent end-wise shifting which might eventually destroy the integrity of the wrapping and permit dulling of 55 the blade. The notches or recesses in the blade

ends may be located centrally and symmetrically or they may be offset toward one edge or the other of the blade according to the design of the blade to be wrapped, and in each case the neck or reduced portion of the end tabs of the 5 wrapper will be correspondingly located.

An important advantage of the present invention is that it may be applied with equal facility to the wrapping of single edged blades or double 10 edged blades.

These and other features of the invention will be best understood and appreciated from the following description of a preferred embodiment 15 thereof, selected for purposes of illustration and shown in the accompanying drawing, in which:

Figs. 1, 2 and 3 illustrate successive steps in the 20 wrapping of a double edged blade having centrally located end recesses;

Figs. 4, 5 and 6 illustrate similar steps in wrapping 25 a single edged blade having non-symmetrically located end recesses;

Fig. 7 is a fragmentary view in perspective 30 showing one end of the blade in Figs. 2 and 3 in position upon its wrapper but before the end tab is folded over the end of the blade.

The wrapper blank, which may be made of 35 thin sheet material such as oiled or waxed paper as shown in Fig. 1, comprises a rectangular body portion 10 scored to define side flaps 11 and 12 and end tabs or tongues 13. Each end tab 13 40 tapers outwardly and is provided with a reduced portion or neck 14 and an enlarged terminal portion 15 having a square cut end edge. In the 45 wrapper of Fig. 1 the reduced portions 14 are symmetrically located centrally in the tabs 13 and 35 the outer portions 15 are symmetrically shaped and located upon the necks 14. The inwardly directed edges of the portions 15 flare outwardly or diverge and thus provide deep reentrant inwardly tapering notches in the side edges of the 40 end tabs. The necks 14 are located entirely outside or beyond the fold lines of the tabs. The reentrant angles formed at the juncture of the said 45 flaps 11 and 12 with the end tabs 13 supply convenient angles for engaging and positively locating the blanks for the wrapping operation. For example, when the wrapping is done by automatic machinery gauge pins may be located at these points.

As herein shown a safety razor blade 20 of the 50 "AutoStrop" type is selected for illustrative purposes. These blades have oppositely disposed cutting edges and unsharpened end edges in each of which is formed a deep notch or recess 21 having parallel side edges and bevelled or flaring out- 55

er corners. The blade 20, or a similar blade, may be presented to the wrapper in automatic machinery by a suction head having nozzles which engage the blade at spaced points and maintain it in position by suction. The head is operated to carry one blade after another from a stack in a magazine into position in alignment with the successive wrappers which may be presented by a rotary turret or other mechanism. In its preliminary position the blade is suspended above the body of the wrapper 10 by substantially the height of the main portion of the end tabs 13. The body of the wrapper and the side flaps 11 and 12 are held flat or substantially so while the end tabs 13 are turned into upright and substantially parallel position, as indicated in Fig. 7. In this condition the end flaps may be folded inwardly and the reduced necks 14 passed into the end recesses 21 of the blade and this folding operation continues until the blade 20 is lowered upon the body 10 of the wrapper. The necks 14 pass fully into the recesses 21 and the terminal enlargements 15 of the end tabs lie flat upon the upper face of the blade. This completes the interlocking engagement of the end flaps with the blade and it will be seen that the necks 14 fit snugly within the recesses 21 so that lateral shifting of the blade is positively prevented. At the same time the inner end of the recess 21 is brought into engagement with the enlarged terminal portions 15 of the flaps so that endwise shifting of the blade in either direction is positively prevented.

The wrapping of the blade may now be completed by folding the side flaps 11 and 12 inwardly upon their fold vertex lines. As shown in Fig. 3 the flap 12 is first folded and then the flap 11 is brought down upon it in overlapping relation, completely enclosing the blade, covering the enlarged terminal portions 15 of the end flaps and preventing displacement thereof. Accordingly, so long as the side flaps are held in closed position, the blade is positively anchored in its wrapper and held against displacement no matter to what usage the protected blade may be subjected.

In Figs. 4 and 5 my invention is illustrated as applied to the wrapping of a single-edged blade 40 having end notches located unsymmetrically and closely adjacent to its rear unsharpened edge. In this case the wrapper comprises a rectangular body portion 30 and side flaps 31 and 32 similar to the corresponding parts of the wrapper shown in Fig. 1. End flaps 33 are also included in the wrapper and each is provided in its outer edge with a reduced portion or neck 34 arranged non-symmetrically and offset toward the fold vertex line of the side flap 31. The necks 34 are thus positioned to register with the end recesses of the blade 40 when the latter is symmetrically located upon the wrapper as shown in Fig. 5. The neck portions 34, as before, terminate in enlarged terminal portions 35 having square-cut end

edges and diverging inner edges which form deep reentrant, inwardly tapering notches in the sides of the end flaps.

In the wrapping operation the blade 40 is presented in alignment with and above the body portion 30 of the wrapper and in such position that the end flaps 33 may be folded beneath the body of the blade while the neck portions 34 are caused to pass into the end recesses of the blade and interlock therewith. As the folding operation continues the enlarged terminal portions 35 are folded downwardly upon the upper face of the blade 40 thus establishing a longitudinally interlocking relation between the two. Finally the blade is completely enclosed by folding the side flap 32 and then the side flap 31 as indicated in Fig. 6.

Having thus disclosed my invention and described two embodiments thereof for purposes of illustration but not limitation, I claim as new and desire to secure by Letters Patents:—

1. A safety razor blade having recessed ends presenting unsharpened edges, in combination with a protecting cover including end tabs folded on a line parallel to said unsharpened edges, the tabs having reduced necks engaging the sides of the recesses and enlarged end portions wider than said recesses.

2. A safety razor blade having recessed ends, in combination with a protecting cover including end tabs with reduced neck portions fitting into the end recesses and enlarged terminal portions overlying the blade between the ends of said recesses, and side flaps covering said terminal portions and the otherwise exposed body of the blade.

3. A protected blade having recessed ends, in combination with a wrapper including a body portion as long as the blade and end tabs folded inwardly over the blade ends on fold lines spaced apart by the full length of the blade, the tabs having reentrant notches forming reduced necks which are received within the end recesses of the blade and enlarged terminal portions engaged with the inner edges of said recesses.

4. A protected blade having a wrapper with tabs folded over both ends thereof, the tabs being symmetrically edge-notched above their respective fold lines and thus provided with centrally located necks to enter similarly located recesses in the blade ends and having at their free ends enlarged portions wider than the recesses in the blade ends.

5. A protected blade having a wrapper with a tab folded over one end thereof, the tab having an unsymmetrically located neck therein located above its fold line, said tab fitting within an offset recess in the blade end and having at its free end an enlarged portion wider than the recess of the blade.

JOSEPH M. BOWEN.
